UNITED STATES PATENT OFFICE.

JAMES H. WATSON, OF RIVERTON, WYOMING.

CASING-JACK.

1,301,769.

Specification of Letters Patent. Patented Apr. 22, 1919.

Application filed September 24, 1918. Serial No. 255,422.

To all whom it may concern:

Be it known that I, JAMES H. WATSON, a citizen of the United States, residing at Riverton, in the county of Fremont and State of Wyoming, have invented certain new and useful Improvements in Casing-Jacks, of which the following is a specification.

The present invention relates to improvements in power jacks for use particularly in well drilling operations.

It may here be explained that owing to the very heavy weight and strains incident to the handling of well casings or long pipe lines, it is necessary to provide very substantial rigging, for it is not unusual for collapses to occur where such precaution is not taken which result in injury to the casing, the well or to the operators. This becomes unnecessary when the work is carried on by my apparatus, thereby saving considerable expense and not only is this true, but in addition my invention enables the raising and lowering operations to be cared for directly by the drilling engine, resulting in the elimination of much wasted time incident to the changing of the drilling appliances from drilling to casing handling.

To this end the apparatus consists of a suitable support carrying driving elements having operative connection with a novel type of jack-screw and provided with a special gripping device forming one of the important features of my apparatus.

Among other features, may also be mentioned the adaptability of my apparatus for imparting to the casing rotative movement which is often desirable in the operation of well drilling.

These and such other objects as may hereinafter appear are attained by the novel construction, combination and arrangement of parts to be hereinafter specifically described and claimed. Reference will now be had to the accompanying drawings forming a part of this specification, wherein:

Figure 1 is a view showing the application of the apparatus in position in relation to the well rigging.

Fig. 2 is a side elevation of the invention, parts being broken away and shown in section.

Fig. 3 is a top plan view.

Fig. 4 is an enlarged fragmentary sectional view showing the head of the jack-

screw and its spiral gear path and driving pinions.

Figs. 5 and 6, are top plan and sectional views of the gripper shoe.

Figs. 7 and 8 are similar views of the gripping blocks.

Throughout the following detail description and on the several figures of the drawings, similar parts are referred to by like reference characters.

65

Referring to Fig. 1 of the drawings, it will be observed that the apparatus which forms the subject-matter of this invention is disposed within the usual pit provided under the floor of the well rigging where it is in position to coact with the upper extremity of the well casing. As a suitable support, I provide the lower base 1 which rests upon the bottom of the pit and the upper base 2 carried by the pillars or posts 3. Upon this upper base is bolted or otherwise secured the cylindrical case or column 4 which constitutes the support for the main mechanism hereinafter described. At diametrical points about the upper portion of the case 4 are provided a series of bearing sleeves 5 which are most clearly seen in Fig. 4, each sleeve having journaled therein a short shaft 6. One of these shafts, namely 6', longer than the others, carries the driving sprocket 7, 85 which is driven from the drilling engine in any suitable manner, as by the chain 8. This shaft 6' referred to is provided with a large driving bevel gear 9, which meshes with an idler 10 on the next shaft, the latter 90 meshing with a second driving gear 11 from which power is transferred to the third and fourth gears 12 and 13 by intermediate idlers 14 and 15. On the inner end of each of the driving shafts thus provided is a pinion 16 95 (see Fig. 4) which meshes with the spiral gear path 17 extending around the jack screw 18 mounted for movement within the case 4. In addition to this gear path the screw 18 is formed with a smooth portion 19 upon which the beveled extremities of the shafts operate to sustain the lifting strains or weight and prevent injury to the gearing.

A discontinuance of the gearing at the upper and lower terminals of the gear path 105 limits the movements of the screw, as will be obvious to those skilled in this art.

As a matter of detail of construction, each of the sleeves contains inner and outer brass boxes 20, 21, between which is received the 110

annular flange 22 on the shaft, for taking up end thrust.

Passing now to the gripping mechanism by means of which the well casing is positively gripped for raising, for example, it will be noted in Fig. 2, that the screw 18 has mounted on its top what I term for the purpose of convenience, the gripper head, consisting of the casting 23, sustained by the ball and race indicated at 24, and the expandable and contractible gripping elements more specifically referred to. Upon this casting are provided four levers 25, though of course the number may be modified as conditions require, and each of these levers carries at its outer end a counterbalance weight 26. The levers are pivoted on the casting by pivots 27 which are of special construction as indicated in Fig. 3 inasmuch as they are provided with ball extremities received between the pairs of clamp connecting members 28, which in turn carry the toggle arms 29 connecting with the pivot pins 30, by means of which arrangement a simultaneous operation of the gripping shoes 31, attached to the ends of the levers 25, is obtained. These shoes are somewhat wedge-shaped at their lower ends, as will be seen in Fig. 2 and act to force their respective gripping block or plate, specifically shown in Fig. 7 and 8, against the well casing. These blocks are preferably serrated on their inner faces so as to afford ample gripping action or prevent slipping and of course are interchangeable with blocks of greater or less thickness to take well casings of different diameters.

This gripping mechanism just described is held on the screw 18 by the adjustable arms 32 and under ordinary conditions remains stationary while the screw rotates. It may, however, be so clamped by tightening these arms that it will rotate with the screw and thereby rotate the casing which is often times desirable in placing casings, as hereinbefore suggested.

A duplicate of this gripper head is mounted on the lower base 1 of the support and operates in exactly the same way, as will be apparent from Fig. 1, the object in the duplication being to provide for holding the casing by one of the gripper heads while the other is being moved for another grip,—in this manner imparting a step-by-step movement to the casing when it is raised or lowered.

Now while I have described the apparatus as applicable especially to the operation of drilling wells, its principles may be employed in other types of operations and I do not wish to be limited in this respect to that described. It will be apparent also that changes may be made in the details of construction of this apparatus without departing from the spirit of the invention and

within the scope of the claims hereto appended.

Having thus described my invention, what I claim as new is:

1. In a power jack of the class described, 70 the combination of a support or standard, a screw revolvably mounted thereon, and actuating means sustaining the screw on said standard having operative connection with the screw to rotate the same and thereby 75 raise and lower the screw.

2. In a power jack of the class described, 70 the combination of a support or standard, a screw revolvably mounted thereon and having an annularly formed gear path, and 80 actuating means on said standard including a driving pinion engaging said path to rotate the screw and thereby raise and lower the screw.

3. In a power jack of the class described, 85 the combination of a support or standard, a screw revolvably mounted thereon and having a spiral gear path formed about the same, actuating means mounted on said standard including a driving shaft and a 90 pinion thereon meshing with the gear path aforesaid whereby to raise or lower the screw.

4. In a power jack of the class described, 95 the combination of a supporting standard, a screw mounted therein for up and down movement and having a spiral gear path formed therein, a driving shaft having driving connection with said gear path and a bearing surface co-operative with the screw 100 adjacent to the gear path to sustain the weight upon the screw.

5. In a power jack of the class described, 105 the combination of a supporting standard, a screw mounted therein having an annular gear path, a driving shaft adapted to be driven from a suitable source of power and having a pinion meshing with the gear path aforesaid at one side of the screw for actuating the same, and separate driving 110 means for said screw arranged to be actuated from the driving shaft aforesaid whereby to distribute the application of the driving power to the screw.

6. In a power jack of the class described, 115 the combination of a supporting standard, a screw mounted therein having an annular gear path, a driving shaft adapted to be driven from a suitable source of power and having a pinion meshing with the gear path 120 aforesaid at one side of the screw for actuating the same, and separate driving means for said screw comprising a series of shafts arranged at diametrical points about the screw and having operative connection with 125 the first mentioned shaft.

7. In a power jack of the class described, 130 the combination of a hollow standard, a screw mounted within the same and having its peripheral wall formed with a spiral

gear rack and a smooth bearing surface adjacent thereto, and a driving shaft operable from a suitable source of power having a driving pinion at its inner end meshing with the rack and a bearing surface operable on the smooth bearing surface aforesaid for sustaining the weight placed upon the screw.

8. In a power jack of the class described, the combination of a hollow standard, a screw mounted within the same and having its peripheral wall formed with a spiral gear rack and a smooth bearing surface adjacent thereto, a driving shaft operable from a suitable source of power having a driving pinion at its inner end meshing with the rack and a bearing surface operable on the smooth bearing surface aforesaid for sustaining the weight placed upon the screw, a series of other shafts arranged about the standard certain of which being provided with pinions meshing with the gearing rack to distribute the driving stresses about the screw, and bearing supports carried by said standard in which the said shafts are journaled.

9. In a well casing jack of the class described, the combination with a support and jack-screw and means for actuating the same, of gripping mechanism mounted on said screw comprising expandable and contractible gripping devices engageable with the well casing, and manual means for actuating said gripping devices simultaneously.

10. In a well casing jack of the class described, the combination with a support and jack-screw and means for actuating the same, of gripping mechanism mounted on said screw comprising a plurality of gripping elements engageable with the well casing at opposite sides, manual means for actuating each of said elements for effecting engagement or disengagement thereof, and means establishing inter-connection between the last mentioned means whereby all of said gripping elements may be operated from any one of the actuating means therefor.

11. In a well casing jack of the class described, the combination with a support and jack-screw and means for actuating the same, of gripping mechanism mounted on the screw consisting of a gripper head, gripping blocks mounted thereon for engagement with the well casing, and a lever pivotally connected to the head for imparting gripping action to said blocks.

12. In a well casing jack of the class described, the combination with a support and jack-screw and means for actuating the same, of gripping mechanism mounted on said screw consisting of a gripper head having a central opening, interchangeable gripping blocks mounted about said opening for engagement with the well casing when introduced into the opening, actuating shoes upon which the blocks are carried, and manual means for actuating said shoes to impart gripping action to the blocks aforesaid.

13. In a well casing jack of the class described, the combination with a support and jack-screw and means for actuating the same, of gripping mechanism mounted on said screw consisting of a gripper head having a central opening, interchangeable gripping blocks mounted about said opening for engagement with the well casing when introduced into the opening, levers pivotally mounted on said head, connecting means intermediate said levers for actuating all of the same from any one thereof, and means intermediate the blocks and the levers for imparting gripping action to the blocks or releasing the same at will.

14. In a well casing jack of the class described, the combination with a support and revoluble jack-screw and means for actuating the same, of a gripper head mounted on said screw, and means adjustable to permit the head to remain relatively stationary with respect to the screw or move therewith at will.

In testimony whereof I affix my signature.

JAMES H. WATSON.
